(57) **CLAIM**

The ornamental design for a decorative swing lamp, as shown and described.

DESCRIPTION

FIG. 1 is a top perspective view of a decorative swing lamp design showing my new design according to a first embodiment;

FIG. 2 is a bottom perspective view of a decorative swing lamp design showing my new design according to the first embodiment;

FIG. 3 is a front view of FIG. 1;

FIG. 4 is a rear view of FIG. 1;

FIG. 5 is a left view of FIG. 1;

FIG. 6 is a right view of FIG. 1;

FIG. 7 is a top view of FIG. 1;

FIG. 8 is a bottom view of FIG. 1;

FIG. 9 is an enlarged view of the selected portion "9" in FIG. 1;

FIG. 10 is an enlarged view of the selected portion "10" in FIG. 1;

FIG. 11 is an enlarged view of the selected portion "11" in FIG. 2;

FIG. 12 is a top perspective view of a decorative swing lamp design showing my new design according to a second embodiment;

FIG. 13 is a bottom perspective view of a decorative swing lamp design showing my new design according to the second embodiment;

FIG. 14 is a front view of FIG. 12;

FIG. 15 is a rear view of FIG. 12;

FIG. 16 is a left view of FIG. 12;

FIG. 17 is a right view of FIG. 12;

FIG. 18 is a top view of FIG. 12;

FIG. 19 is a bottom view of FIG. 12;

FIG. 20 is an enlarged view of the selected portion "20" in FIG. 12;

FIG. 21 is an enlarged view of the selected portion "21" in FIG. 13;

FIG. 22 is a top perspective view of a decorative swing lamp design showing my new design according to a third embodiment;

FIG. 23 is a bottom perspective view of a decorative swing lamp design showing my new design according to the third embodiment;

FIG. 24 is a front view of FIG. 22;

FIG. 25 is a rear view of FIG. 22;

FIG. 26 is a left view of FIG. 22;

FIG. 27 is a right view of FIG. 22;

FIG. 28 is a top view of FIG. 22;

FIG. 29 is a bottom view of FIG. 22;

(Continued)

FIG. 30 is an enlarged view of the selected portion “30” in FIG. 22;

FIG. 31 is an enlarged view of the selected portion “31” in FIG. 23; and,

FIG. 32 is an enlarged view of the selected portion “32” in FIG. 24.

The broken lines shown on the drawings depict portions of the decorative swing lamp that form no part of the claimed design.

Any shading and cross-hatching are not features of the design but are utilized to illustrate the surface contours of the decorative swing lamp design in the drawings.

1 Claim, 32 Drawing Sheets
